ATTORNEY.

UNITED STATES PATENT OFFICE.

CARL G. HALLBERG, OF MANITOWOC, WISCONSIN.

WINDOW SCREEN.

Application filed March 28, 1922. Serial No. 547,466.

To all whom it may concern:

Be it known that I, CARL G. HALLBERG, a citizen of the United States, residing at Manitowoc, in the county of Manitowoc 5 and State of Wisconsin, have invented certain new and useful Improvements in Window Screens, of which the following is a specification.

This invention relates to adjustable metal 10 window screens, and has for one of its objects to improve the construction and increase the efficiency and utility of devices of this character.

Another object of the invention is to provide 15 a device of this character having improved means for securing the screen material to the frame members.

With these and other objects in view, the invention consists in certain novel features 20 of construction as hereinafter shown and described and then specifically pointed out in the claims, and in the drawing illustrative of the preferred embodiment of the invention:—

25 Figure 1 is a side elevation of one of the improved screen frames.

Fig. 2 is an enlarged section on the line 2—2 of Fig. 1.

Fig. 3 is an enlarged end view of the 30 improved screen frames.

Fig. 4 is an enlarged detail perspective view of one corner of one of the frame units, illustrating the construction, and the manner of uniting the members.

35 Fig. 5 is an enlarged transverse section on the line 5—5 of Fig. 4.

Fig. 6 is a view similar to Fig. 5, illustrating a slight modification in the transverse form of the frame sections.

40 A window screen, in accordance with this invention, is constructed from a sectional screen body formed of a pair of associated U-shaped frame sections telescopically connected together and capable of being adjusted for the adaption thereof in connection 45 with window frames of varying widths.

Each of the frame sections of the screen is constructed from sheet metal and embodies a pair of sides and an end member, 50 each bent into L-shaped form transversely to provide webs 10, 11, disposed at right angles with respect to each other. The webs 10, are wider than the webs 11, and each of the latter is extended, as at 12, and the 55 marginal portion of the extension is bent inwardly as at 13, to provide a guide rib.

The inner marginal portion of each of the webs 10, is folded upon itself to form a channel 14, for the reception of one edge of a foraminous sheet, as indicated at 15. 60 After the foraminous sheet 15, has been positioned in the channels formed on the side and end member of a frame section, the material which provides one wall of the channel is indented so as to extend in the 65 foraminous sheet 15, as indicated at 16, whereby the foraminous sheet 15, is secured to the frame sections.

The extensions 12, of each side and end members of the frame sections abut and 70 have a mitered joint therebetween. The folded marginal portion of the webs 10 of an end member is cut away at each end whereby the ends of the channel 14, will be positioned in spaced relation with respect 75 to the ends of the end member. The folded marginal portions of the webs 10, of the side members terminate at points removed from the outer ends of said webs 10, but the outer end of the said folded marginal portion is 80 arranged in close proximity to an end of a folded marginal portion of an end member.

The webs 10, of the side members overlap the ends of the webs 10, of an end member and are secured together by the hold-fast devices 17. Each frame member, at 85 each corner thereof, is provided with L-shaped reinforcing or brace plates 19, which are angle shaped in contour and are fixedly secured in position by the hold-fast 90 device 20, as clearly shown in Figure 1.

The free ends of the turned folded portions 14 are coupled by stay members 21 which are united thereto by rivets 22, and with one edge of each stay turned inward 95 toward the adjacent foraminous sheet, as shown at 24.

The free ends of the folded portions 14 are coupled respectively by stay members each formed of a metal strip 21 bent into 100 U-shape transversely to embrace the foraminous sheet 15 and secured thereto by imbedding the material of the strip into the foraminous sheet by a center punch or like implement, as illustrated at 22 in Fig. 2. 105

The stay members are secured to the overturned portions 14 by rivets or the like, and the inturned portions of said stay members form effectual stops to prevent the passage of flies and other insects.

110 The overturned portions 14 of the inner telescoping side members of the frame por-

tion, do not extend beyond the stay member 21 of the inner frame members, as indicated at 25 in Fig. 1, so that the frame portions do not fully overlap when closed, or 5 fully collapsed.

A thumb lug 26 is attached to the inner frame member, to facilitate the operation of moving the screen longitudinally to remove them from or insert them in a window.

10 Formed in the web 11 of the outer frame member are slots 27 to receive holding screws or the like to enable the screen frame to be attached permanently to the window frame, if required.

15 The improved device is simple in construction, can be manufactured of any suitable material, and of any required size to adapt it to windows of varying widths.

20 The preferred embodiment of the invention is disclosed in the drawings and set forth in the specification, but it will be understood that modifications within the scope of the claimed invention may be made in the construction without departing from 25 the principle of the invention or sacrificing any of its advantages.

25 The frame sections are shown oblong transversely in Figs. 2, 4 and 5 which will be the form preferably employed for the 30 longer or full length screens, while the form shown in Fig. 6 will preferably be employed for the shorter or sash length screens.

Having thus described the invention, what is claimed as new is:—

35 1. A window screen comprising a frame formed of a pair of U-shaped telescopic sections, each consisting of an end member and a pair of side members, each of said members formed of a pair of webs disposed at 40 right angles with respect to each other, one of said webs of each member having the free marginal portion thereof bent at right angles to provide an L-shaped guide rib of a length equal to the length of the web, and 45 the other of the webs of each member having the free marginal portion thereof folded upon itself and cutaway to provide a channel of less length than the length of the web, a foraminous sheet extended into 50 the channel of each of said frame sections,

a U-shaped stay member connected to the side members of each frame section and registering with the channels of its respective side members and further having said sheet extending therein, the said folded 55 marginal portions of each frame section and of each stay member having inherent means for securing said sheet to its respective frame section, and each of said stay members having one longitudinal side thereof disposed at right angles to abut against a sheet, said right angular portions of said stay members forming stops and further providing 60 closures between said sheets.

2. A window screen comprising a frame 65 formed of a pair of U-shaped telescopic sections, each consisting of an end member and a pair of side members, each of said members formed of a pair of webs disposed at right angles with respect to each other, one 70 of said webs of each member having the free marginal portion thereof bent at right angles to provide an L-shaped guide rib of a length equal to the length of the web, and the other of the webs of each member having the free marginal portion thereof folded 75 upon itself and cutaway to provide a channel of less length than the length of the web, a foraminous sheet extended into the channel of each of said frame sections, a 80 U-shaped stay member connected to the side members of each frame section and registering with the channels of its respective side members and further having said sheet extending therein, and said folded marginal 85 portions of each frame section and of each stay member having inherent means for securing said sheet to its respective frame section, and each of said stay members having one longitudinal side thereof disposed at 90 right angles to abut against a sheet, said right angular portions of said stay members forming stops and further providing closures 95 between said sheets, and combined reinforcing and coupling plates of angle shape secured to the inner faces of each frame section at the corners thereof.

In testimony whereof, I affix my signature hereto.

CARL G. HALLBERG.
